INVENTOR
BEN G. CAMPBELL

by Frank Waterfield
ATTORNEY.

UNITED STATES PATENT OFFICE.

BEN G. CAMPBELL, OF FRESNO, CALIFORNIA.

SEPARABLE PISTON.

Application filed May 9, 1923. Serial No. 637,719.

To all whom it may concern:

Be it known that I, BEN G. CAMPBELL, a citizen of the United States, and resident of Fresno, in the county of Fresno, State of California, have invented certain new and useful Improvements in Separable Pistons, of which the following is a specification.

My invention relates primarily to pistons used in explosion engines and the like having packing rings.

Heretofore, in explosion engines, when it has been desired to replace the piston rings for any reason it has been necessary to dismantle the engine and disconnect the connecting rods from the cranks, and remove the piston and connecting rod, which necessitated considerable labor and inconvenience as well as the expenditure of considerable time.

It is the object of my invention to provide a separable piston so constructed and arranged as to be easily and quickly detached from or replaced in its position of use.

Another object is to provide in a piston of the above character means whereby the portion thereof in which the rings are mounted may be easily and quickly separated or detached from the remainder of the piston for removal from the cylinder.

Other objects and advantages will appear hereinafter, and, while I have shown and will describe the preferred form of my invention, I wish it understood that I do not limit myself to such preferred form but that various changes and adaptations may be made therein without departing from the spirit of my invention.

In the drawings accompanying and forming a part hereof:

Fig. 1 is a central longitudinal section through a piston constructed according to my preferred form.

Fig. 2 is a top plan of Fig. 1.

Fig. 3 is an enlarged fragmentary detail of a modified form.

Fig. 4 is a central longitudinal section of another form of my device.

Fig. 5 is a similar view to Fig. 4 taken at right angles thereto.

Fig. 6 is a top plan, partly in section, of Fig. 4.

Referring to the drawings, my preferred form comprises a piston body composed of two parts, the skirt portion 8 and the ring portion 9. The skirt portion 8 is provided

with the usual wrist pin bearings 10 and the ring portion 9 is provided with the usual ring grooves 11. Provided around the upper edge of skirt portion 8 is an upwardly extending annular flange 12 the outer edge of which lies flush with the outer wall of skirt portion 8, and provided around the lower edge of ring portion 9 is a downwardly extending flange 13 which is of a size and configuration to snugly fit within the annular flange 12 of skirt portion 8, forming a substantially tight dovetail connection therebetween. Extending upwardly from the top of bearings 10, about centrally of their length, are bosses 14 and 15, and mounted at one end in bosses 14 and 15, in screwthreaded engagement therewith, are studs 16 and 17. Pins 18 and 19, passing through bosses 14 and 15 and the lower ends of studs 16 and 17, hold the same securely positioned against displacement. Studs 16 and 17 extend upwardly from bosses 14 and 15 and pass through apertures 20 and 21 in the top wall of ring portion 9. Provided in the top wall of ring portion 9, to open outwardly, and concentric with apertures 20 and 21, are recesses 22 and 23 in which are mounted nuts 24 and 25 in screwthreaded engagement with the upper ends of studs 16 and 17. Nuts 24 and 25 are provided with slots 26 and 27 by means of which the same may be rotated. Provided centrally of the top wall of ring portion 9, to extend partially therethrough, is a screwthreaded aperture 28 in which is positioned a tool, not shown, for removing or replacing the ring portion 9 of the piston from or to the cylinder.

In Fig. 3 the construction of my device is substantially the same as in Figs. 1 and 2, with the exception that a screwthreaded connection is provided between flanges 12 and 13 in lieu of the studs 16 and 17 and their complemental parts, and apertures 29 and 30 are provided in the top wall of ring portion 9 for the reception of a suitable tool for rotating the portion 9 of the piston.

In the form shown in Figs. 4, 5 and 6, my piston comprises two parts, the skirt portion 31 and the ring portion 32, divided transversely on a line passing centrally through the wrist pin bearings 33 and 34 and being provided with a dovetail connection 35. The lower portions of bearings 33 and 34 are carried by the skirt portion 31, and the upper portions of bearings 33 and 34

are carried by the ring portion 32. Extending outwardly from the sides of bearings 33 and 34 are ears 36 and 37, ears 36 being carried by the skirt portion 31 of the piston and 5 being screwthreaded, and ears 37 being carried by the ring portion 32 and being provided with apertures 38 through which pass the lower ends of bolts 39 and 40 the lower ends of which are in screwthreaded engagement with ears 36. Bolts 39 and 40 extend upwardly, pass through apertures 41 and 42 in the top wall of ring portion 32 and terminate in round heads 43 and 44 mounted within recesses 45 in the top wall of ring portion 32. Heads 43 and 44 are provided with slots 46 for the reception of a suitable tool for positioning said bolts. Provided centrally of the top wall of ring portion 32 is a screwthreaded aperture 47 for the reception 10 of a suitable tool for handling the piston during its removal and replacement from and to the cylinder.

In the operation of my device the parts will normally be in the positions shown when 15 in their operative positions. When it is desired to replace the rings, the nuts 24 and 25 will be removed by means of a screw driver or other suitable tool. A suitable tool will

then be inserted in aperture 28 and the ring portion 9 may then be withdrawn from the cylinder. The replacement of portion 9 will be carried on in a reverse order from the foregoing.

Having described my invention, what I claim is:

A separable piston comprising a head portion and a skirt portion; a flange extending upwardly around the upper edge of said skirt portion; a flange depending downwardly around the lower edge of said head portion adapted to fit snugly within the flange of the skirt portion; a pair of opposed bearings in said skirt portion; a boss extending upwardly from each of said bearings; a stud rigidly secured at its lower end in each of said bosses to extend upwardly; apertures in the top wall of said head portion through which said studs pass; a recess in the outer face of said top wall concentric with the apertures therein; and a nut for 40 said studs mounted in each of said recesses in threaded engagement with said studs.

In witness that I claim the foregoing I have hereunto set my hand this 4th day of April, 1923.

BEN G. CAMPBELL.
